WILLIAM CRAIG, OF UNIONTOWN, PENNSYLVANIA.

Letters Patent No. 73,167, dated January 7, 1868.

IMPROVEMENT IN FLOUR-BOLTS.

The Schedule referred to in these Letters Patent and making part of the same.

TO ALL WHOM IT MAY CONCERN:

Be it known that I, WILLIAM CRAIG, of Uniontown, in the county of Fayette, and State of Pennsylvania, have invented a new and improved Flour-Bolt; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved flouring-mill, taken in the plane of the line $x\ x$, fig. 2.

Figure 2 is a plan, with some portions of the mill removed to exhibit the interior arrangement of the elevators and double bolting-cloths.

Figure 3 is a transverse section of the bolting-chest, taken in the line $y\ y$, fig. 1.

Similar letters of reference indicate like parts.

This invention relates to an improved flour-bolt in a portable flouring-mill, and consists of two hexagonal cloths, arranged one within the other on the same reel, and separated by a close partition-cloth, as will be hereinafter more fully described. The general arrangement of a portable mill is also shown, to which my improved bolt is applied.

Two run of thirty-six inch burr-stones are set side by side, as shown in plan, fig. 2. The upper stone, A, is made stationary, and the lower stone, A', is the runner. They are to be set in cast-iron frames, and the lower one supported by an iron plate. The hoppers B are arranged in the ordinary way. The stones are both operated directly by one horizontal spur-wheel, a, which is placed between them, below on the shaft a^1 , and gears into pinions, a^2 , on the spindles. On the shaft a^1 is placed a pulley, b, to be connected by a belt with a driving-pulley operated by steam or water-power. Under the main wheel a, on the same shaft, is placed a bevel-wheel, e, gearing into the bevel e' on the shaft f, which passes horizontally through the bottom of the elevator-box Z, containing double flour-elevators. The shaft f extends beyond the elevator-box Z, and carries the long screw-conveyor C; and on its outer extremity is placed a bevel-wheel, g, which gears into the bevel g' on the vertical shaft h, carrying the bevel-gear $i\ i'$, for operating the conveyor D directly, and the short conveyor E above, by means of cog-gear $k\ k'$. The shaft h also operates the bolting-apparatus, by means of cog-gear l on its upper end, and l' on the shaft F of the bolt-reel m.

The double elevators in the trunk Z are constructed in the usual way. n n are the elevators or belts, provided with buckets, and running over the rollers s s at the upper end, and t t at the lower end, on the shaft f. The double elevators are separated by a partition, u. They receive the flour from the two run of stones by separate spouts, u¹ u², and deliver it, by separate spouts, u³ u⁴, into separate bolting-cloths, through the head m² of the chest G.

My improved bolting-apparatus consists of two hexagonal cloths, arranged, one within another, on the same reel, m. v is the inside and v¹ the outside bolting-cloth, separated by a close partition-cloth, v², all of which are fastened to the reel by ribs, m¹, and are so constructed and arranged that the outside and inside bolting-cloths shall receive the flour separately from the double elevators, and deliver it, as bolted, into separate divisions or compartments of the bolting-chest, according to the different qualities or grades of flour and bran. The bolting-cloths v v¹ are secured to the reel m by placing the ribs m¹ on the outside instead of the inside, as usual, giving a continuous smooth surface on the inside of the bolts, so that the flour slides from one end to the other without interruption, carrying the bran along smoothly in front, instead of being raised and thrown down by the ribs when placed on the inside, as usual, which forces fine particles of bran through the cloth, and specks the flour.

The inside bolting-cloth v extends from end to end of the chest G, the bolted flour of finest quality falling upon the partition-cloth v², which delivers it into the transverse compartment H in the chest G, while the next lower grade of flour falls into the compartment I, and the bran falls from the outer end into the compartment K.

The outside bolting-cloth v¹ is shorter than the partition-cloth v², and the finer flour falls directly into the large compartment M, while the bran falls from the end of the bolting-cloth into the compartment L.

The compartments K L are provided with side spouts, w w, for discharging the bran, and the chamber with the spout w¹, for the inferior flour.

The compartment H, which receives the fine flour from the inside bolting-cloth v, opens into the box of the

short conveyor E, which is provided with a spout to discharge the flour by itself, when desired, and also with a trap-slide to discharge it into the box of the conveyor D, to mix it with the flour from the outside bolting-cloth v^1 .

Both run of stones may thus grind grain of one kind, or two kinds of grain may be ground at the same time on separate stones, and the flour kept separate.

The conveyor D is provided with spouts, w^2 , in the usual way, for discharging different grades of flour, and also with return-spouts, w^3 , which discharge into the box of the long conveyor C, by which the coarser flour is conducted to the elevator, to be carried by it to the bolting-apparatus to be rebolted.

I do not claim the separate parts of my device as new in themselves, but

I do claim the bolt, constructed as described, having the partition v^2 between the outer and inner bolting-cloths v v^1 , operating substantially as described, for the purpose specified.

WILLIAM CRAIG.
